(74) *Attorney, Agent, or Firm* — Sheridan Ross P.C.

(57) **CLAIM**

The ornamental design for a syringe restrictor plate, as shown and described.

DESCRIPTION

FIG. 1 is a front perspective view of the syringe restrictor plate;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a perspective view thereof, shown in its environment;

FIG. 9 is a front perspective view of the syringe restrictor plate according to another embodiment;

FIG. 10 is a front elevation view of the embodiment of FIG. 9;

FIG. 11 is a rear elevation view of the embodiment of FIG. 9;

FIG. 12 is a right elevation view of the embodiment of FIG. 9;

FIG. 13 is a left elevation view of the embodiment of FIG. 9;

FIG. 14 is a top plan view of the embodiment of FIG. 9;

FIG. 15 is a bottom plan view of the embodiment of FIG. 9; and,

FIG. 16 is a perspective view of the embodiment of FIG. 9, shown in its environment.

The broken lines showing a tub depict environmental subject matter that forms no part of the claimed design. All other broken lines depict portions of the syringe restrictor plate that form no part of the claimed design.

1 Claim, 12 Drawing Sheets
